UNITED STATES PATENT OFFICE.

THOMAS A. REYNOLDS, OF CRAFTON, PENNSYLVANIA, ASSIGNOR TO THE McCONWAY & TORLEY COMPANY, OF PITTSBURGH, PENNSYLVANIA, A CORPORATION OF PENNSYLVANIA.

MOLDING MACHINE.

1,417,568.

Specification of Letters Patent. Patented May 30, 1922.

Application filed March 24, 1921. Serial No. 455,023.

To all whom it may concern:

Be it known that I, THOMAS A. REYNOLDS, a citizen of the United States, residing at Crafton, in the county of Allegheny and State of Pennsylvania, have invented certain new and useful Improvements in Molding Machines; and I do hereby declare the following to be a full, clear, and exact description of the invention, such as will enable others skilled in the art to which it app pertains to make and use the same.

The invention relates to a molding machine and has for its object to produce a simple and efficient apparatus by which molds or cores can be rapidly and economically made.

The principal features of the invention are embodied in an organization involving a chute for delivering the molding sand to an aligned succession of mold boxes which are intermittently moved from beneath said chute into operative relation with a fluid pressure controlled ramming device by which the sand is pressed in the boxes, the operation of the ramming device being controlled by the movement of a valve which is operatively coordinated with the means by which the mold boxes are shifted.

A further feature of my invention consists in employing a fluid pressure controlled ramming device having a pressure cylinder which communicates with a conduit through which fluid pressure may be introduced and permitted to exhaust, the said conduit being adapted to be placed in communication alternately with a source of fluid pressure and with the atmosphere through the instrumentality of a valve device whose movement is coordinated to that of the mechanism by which the mold boxes are shifted.

A further feature of the invention consists in providing means for supplying the mold boxes with loose sand in excess of that required to fill them and in pressing the sand in said boxes by means of a ramming device which is provided with a rammer head adapted to permit the escape of surplus sand.

A still further feature of the invention involves the operative connection of the fluid pressure ramming device with the valve by which it is controlled through the intervention of a conduit having a portion which is movable with the valve.

Another feature of the invention consists

in intermittently shifting a series of mold boxes by means of a reciprocating member which is adapted to engage successive boxes and which has a stroke exceeding the movement imparted to the boxes between their periods of rest.

There are other features of invention residing in special combinations of parts and details of construction, all as will herein-after appear.

In the drawings illustrating the preferred form in which I contemplate applying the principle of the invention, the scope whereof is pointed out in the claims.—

Figure 1 is a side elevation of a molding machine embodying the invention, portions of the supporting legs or standards, of the sand chute, of the fluid pressure piping and of the driving mechanism being broken away.

Figure 2 is a plan view of the apparatus shown in Fig. 1, parts of the sand chute and of the fluid pressure piping being omitted.

Figure 3 is an enlarged view in end elevation of the construction shown in Figs. 1 and 2, portions of the piping and of the driving mechanism being omitted.

Figure 4 is a detail plan view of the valve mechanism and associated parts.

Figure 5 is a detail sectional view on the line 5—5, Fig. 4.

Figure 6 is a detail sectional view on the line 6—6, Fig. 4, the valve being in the position it occupies when the fluid pressure is being exhausted from the ramming device to the atmosphere.

Figure 7 is a view corresponding to Fig. 6, but illustrating the position of the valve when fluid pressure is passing to the cylinder of the ramming device.

Figure 8 is a detail sectional view of the rammer head taken on the line 8—8, Fig. 3.

The framework of the apparatus preferably consists of laterally spaced channel members 1 and 2, respectively, whose backs are arranged uppermost in the same horizontal plane to form a support for a series of slideable mold boxes 3. The form of mold boxes will, of course, vary with the form of mold or core to be made, the boxes illustrated in the drawings being particularly designed for the molding of what are known as pouring boxes. The channels 1 and 2 may be elevated from the floor or foundation to a

height convenient for the attendant of the apparatus by means of legs or standards 4 which are rigidly connected to said channels.

Laterally spaced guide members 5 and 6, respectively, between which the mold boxes 3 are adapted to pass, are preferably employed for maintaining the alignment of said boxes during their passage through the apparatus. These guide members, as shown, 10 may conveniently be formed as angle irons whose horizontal flanges are riveted to the respective channel members 1 and 2, and whose vertical flanges, which are adapted to engage the sides of the boxes, are preferably 15 of a height sufficient to enable them to extend above the tops of said mold boxes. The guide member 5 is of less length than the guide member 6, thus enabling empty mold boxes to be readily placed in position on the 20 supporting channels 1 and 2 at one end of the apparatus and permitting the mold boxes containing the finished molds to be easily removed at the other end of the machine.

Extending upwardly above said guide 25 members 5 and 6 is a frame affording a support for a fluid pressure ramming device 7. This frame may be formed of angle irons 8, 8 and 9, 9 which are rigidly connected at their lower ends to the outer faces of the 30 guide members and which are firmly united at their upper ends by being riveted to tie plates 10. Extending between the angle irons 8 and riveted thereto is a plate 11 to which the flanges 12 of the cylinder ramming device 13 may be secured by means of 35 bolts 14.

The chute 15, which may be secured in any desired manner, is positioned so as to deliver molding sand to the successive mold boxes 40 3 prior to their reaching the ramming device 7.

With the exception of the rammer head 16, the fluid pressure ramming device may be, and preferably is, constructed like an air-brake cylinder commonly in use upon railway cars; that is to say, the piston 17 within the cylinder 13 is provided with a piston rod 18 which is encircled by a spring 19 that by being interposed between the piston and 45 one end of the cylinder normally operates to retain the piston 17 in a position corresponding to the elevated position of the rammer head 16. The cylinder 13 is connected on one side of the piston 17 with a pipe or conduit 20 through which fluid pressure may be 50 introduced into and exhausted from the cylinder.

The plunger head or rammer 16, which is secured to the outer end of the piston rod 55 18, is adapted to press the sand in the mold box positioned therebeneath when the piston 17 is forced downwardly by the admission of compressed air to the cylinder 13. When the air in the cylinder is allowed to exhaust 60 to the atmosphere through the pipe 20 the

spring 19, acting upon the piston 17, causes a retractile movement of the rammer head 16 which elevates the latter sufficiently to allow the mold box in which the sand has been compressed to be shifted and a new 70 mold box to be positioned beneath the ramming device. Since it is preferred, as will hereinafter appear, to construct the apparatus so that the mold boxes 3 are supplied with loose sand from the chute 15 in excess 75 of the amount required to fill them, it is desirable that the rammer head 16 shall be of a form enabling surplus sand to escape. In the form of rammer head 16 illustrated in the drawings provision for the escape of 80 surplus sand is made by providing said head with a central opening 21. When, as in the case illustrated in the drawings, the mold boxes 3 are provided with interior projections 22, the opening 21 in the rammer head is preferably located so that it stands immediately above the projection in the mold box upon which the ramming device is operating. This allows the pressure 85 of the rammer head to be efficiently applied 90 to press the sand well down in the mold box.

The mold boxes resting upon the supporting channels 1 and 2 are intermittently shifted thereon between the guides 5 and 6 95 to position them successively beneath the sand delivering chute 15 and the ramming device 7. For this purpose it is preferred to employ a reciprocating member or shoe 23 which rides upon the upper surfaces of the 100 channels 1 and 2 upon which the mold boxes 3 are slidably supported. This reciprocating shoe is provided with a vertically extending portion 24 adapted to move into contact with each succeeding mold box that 105 is placed in position in the apparatus. The reciprocation of the shoe 23 thus causes the mold boxes to move through the molding machine in a step-by-step manner, the sand being delivered to the boxes and being 110 pressed therein while said boxes are at rest. The reciprocation of the box actuating shoe 23 is preferably effected by a pitman 25 which is connected to a continuously rotating crankshaft 26 and to said shoe by suitable connecting pins 27 and 28, respectively. To prevent the possibility of any vertical movement of the reciprocating shoe 23, it is preferred to attach to the bottom thereof, as 115 by means of cap screws 29, a shouldered 120 plate or block 30 which extends under the adjacent vertical legs of the channels 1 and 2.

Each of the mold boxes 3 carries away 125 from the chute 15 a surplus of loose sand extending in a layer above the top of the boxes. To this end the apparatus is provided with a reciprocating slide 31 which is adapted to enter the space between the lower end of the chute 15 and the mold box which 130

is below the chute. This slide which is movable with the reciprocating shoe 23 and is preferably connected thereto by means of the pin or bolt 28, passes under the end of 5 the chute in unison with the movement of the mold box as the latter is moved from beneath the chute to its operative relation with the ramming device 7. This enables each mold box to carry to the ramming device 10 a quantity of loose sand more than sufficient to fill the box. The slide 31 is preferably made of plate-like form and of a width sufficient to extend completely across the lower end of the chute 15, the delivery 15 of sand to the next succeeding mold box thereby being cut off until an empty mold box is in proper position below the chute. As shown in Fig. 1, the reciprocating member 23 by which the mold boxes are shifted 20 preferably has a stroke of somewhat greater length than the movement imparted to said boxes between their periods of rest. By this means ample clearance is provided between the reciprocating shoe 23 and the adjacent 25 end of the guide 5 for the easy insertion of empty mold boxes. For convenience in supporting the empty mold boxes 3 prior to their insertion in the apparatus in front of the reciprocating shoe 23, an angle iron 30 32 may be riveted to the supporting channel iron 1 so that its horizontal flange is in the same plane as the upper surface of said channel.

A scraper 33, which may be conveniently 35 formed of an angle iron, extending obliquely between and riveted to the vertical webs of the mold box guides 5 and 6, respectively, is preferably provided for removing from the tops of the mold boxes 3 any surplus 40 sand which may remain after said boxes have passed beneath the ramming device 7. Excess sand accumulating and banking up against the scraper may be manually removed by the operator as occasion requires.

45 The operation of the sand ramming device 7 is controlled by means of a valve mechanism whose movement is coordinated to that of the reciprocating shoe by which the mold boxes are intermittently shifted. This 50 valve mechanism preferably comprises an oscillating valve plate 34 which is pivotally mounted intermediate its ends on a bolt 35 carried by a stationary valve seat 36. The latter is formed with a port 37 which is connected to a pipe or conduit 38 leading to an air compressor or other suitable source of fluid pressure (not shown), and said valve seat is also provided with a port 39 that is 55 connected to a pipe or conduit 40 which opens to the atmosphere. The valve seat 36 may be secured by means of bolts 41 to an arch or yoke 42 whose outturned lower ends are respectively secured to the bearings 43 of the crank shaft 26 by means of bolts or 60 cap screws 44. The oscillating valve 34 has

a port 45 which is adapted to register alternately with the ports 37 and 39 respectively communicating with the conduit 38 leading to the source of fluid pressure and with the exhaust pipe 40 leading to the atmosphere. 70 The port 45 is connected to the conduit 20 leading to the cylinder 13 of the ramming device, a portion 46 of said conduit being flexible to allow oscillation of the valve 34 and preferably being a section of rubber hose. 75 On the opposite side of its pivot from the port 45 the valve is preferably provided with a cam roller 47 which is revolubly mounted upon a pivot pin 48 projecting downwardly from the under side of said valve. This cam roller enters and cooperates with a cam groove 49 formed in a sleeve 50 which is rigidly secured to the crankshaft 26. At each revolution of the shaft 26 the valve 34 is moved so that the pipe 20 is successively 80 placed in communication with the source of fluid pressure through the pipe 38 and with the atmosphere through the pipe 40, the valve mechanism being so timed that the rammer head 16 of the ramming device is 85 maintained in elevated position during the shifting of the mold boxes 3 and is forced downwardly to press the sand in the boxes when the latter are at rest.

The crankshaft 26 rotates continuously in 90 one direction. It may be driven in any suitable manner, but it is preferred to employ an electric motor 51 and reducing gearing for that purpose. The shaft 52 of the electric motor, when such is employed, is preferably provided with a pinion 53 which meshes with a larger pinion 54 that is mounted upon a shaft 55 carrying a smaller pinion 56 at its opposite end. This latter pinion meshes with a larger pinion 57 secured to 100 the crankshaft 26.

It will be perceived that no manual labor is required for the operation of a molding machine involving my invention beyond that required to feed the empty mold boxes in 110 the apparatus and to remove the filled mold boxes therefrom.

I claim:

1. In a molding machine, the combination with mold box supporting means, of a series of mold boxes slidably supported on said means, reciprocating means adapted to engage successive mold boxes to effect an intermittent shifting thereof upon said supporting means, stationary means for supplying sand to successive mold boxes, means movable with said reciprocating means for controlling the supply of sand from said sand supplying means, and means for pressing the sand in successive mold boxes. 115

2. In a molding machine, the combination with mold box supporting means, of a series of mold boxes slidably supported on said means, means for causing said boxes to move successively into alinement with an opening 130

in a sand delivering chute and thereafter into alignment with a sand ramming device, a sand delivering chute for supplying sand to said boxes, means adapted to move in one direction with said boxes and to move in the opposite direction independently of said boxes for causing each of the latter to carry away from said chute a layer of sand extending above the top of the box, and a ramming device for pressing the sand in successive mold boxes.

3. In a molding machine, the combination with means for slidably supporting a series of mold boxes, said means being provided with guides for maintaining said boxes in alignment, of means for causing said boxes to move successively under an opening in a sand delivering chute and thereafter under a sand ramming plunger, means for intermittently shifting said boxes with respect to said supporting means, and means operatively coordinated with said box shifting means for causing said plunger to press the sand in one of said mold boxes during the delivery of sand to another of said mold boxes.

4. In a molding machine, the combination with means for slidably supporting a series of mold boxes, of means for delivering sand to said boxes, a ramming device adapted to press the sand in said boxes, fluid pressure mechanism governing the operation of said ramming device, and means for intermittently shifting said boxes with respect to said supporting means to bring successive boxes into operative relation with said ramming device, said ramming device involving a cylinder, a piston within said cylinder having a piston rod provided with a sand ramming head, and a spring adapted to move said piston in one direction, and said fluid pressure mechanism comprising a conduit communication with said cylinder through which fluid pressure may be introduced into and exhausted from said cylinder, a conduit connected to a source of fluid pressure, and a valve device operatively coordinated with said box shifting means for alternately establishing communication between the conduit communicating with said cylinder and the conduit connected to the source of fluid pressure and permitting the fluid pressure in said cylinder to exhaust through said first named conduit.

5. In a molding machine, the combination with means for slidably supporting a series of mold boxes, of means for delivering sand to said boxes, a fluid pressure controlled ramming device adapted to press the sand in said boxes, fluid pressure mechanism governing the operation of said ramming device, said mechanism including a valve, and means for intermittently shifting said boxes with respect to said supporting means to bring successive boxes into operative rela-

tion with said sand delivering means and with said ramming device, said means for shifting said boxes including a continuously rotating shaft, and said valve being adapted to be actuated by a cam mounted upon said shaft.

6. In a molding machine, the combination with means for movably supporting a series of mold boxes, of means for supplying said boxes with sand, a ramming device for pressing the sand in successive boxes, and means for moving said boxes into operative relation with said sand supplying means and thereafter into operative relation with said ramming device, said ramming device being provided with a rammer head adapted to permit the escape of surplus sand.

7. In a molding machine, the combination with means for movably supporting a series of mold boxes, of means for supplying said boxes with loose sand in excess of that required to fill them, a ramming device for pressing the sand in successive boxes, a scraper beneath which said boxes are adapted to pass, and means for successively moving said boxes into operative relation with said sand supplying means and ramming device and for causing them thereafter to pass beneath said scraper, said ramming device being provided with a rammer head adapted to permit the escape of surplus sand, and said scraper being adapted to remove surplus sand.

8. In a molding machine, the combination with means for movably supporting a mold box, of means for supplying sand to said mold box, a ramming device for pressing the sand in said mold box, and means for moving said mold box into operative relation with said ramming device, said ramming device being provided with a rammer head having an opening therein permitting the escape of sand.

9. In a molding machine, the combination with means for slidably supporting a series of mold boxes, of means for supplying sand to said boxes, a ramming device for pressing the sand in said mold boxes, and means for intermittently shifting said boxes with respect to said supporting means to bring them successively into operative relation with said sand supplying means and said ramming device, said box shifting means involving a reciprocating member adapted to engage succeeding mold boxes and having a stroke of greater length than the movement imparted to said boxes between their periods of rest.

10. In a molding machine, the combination with means for slidably supporting a series of mold boxes, of means for supplying sand to said boxes, a ramming device for pressing the sand in said boxes, and means for intermittently shifting said boxes on said supporting means to bring them succes-

sively into operative relation with said sand supplying means and said ramming device, said box shifting means involving a reciprocating member adapted to engage succeeding 5 mold boxes, a continuously rotating crank shaft, and a pitman operatively interposed between said reciprocating member and said shaft.

11. In a molding machine, the combination with means for movably supporting a 10 series of mold boxes, of means for delivering sand to said boxes, a fluid pressure controlled ramming device for pressing the sand in said boxes, fluid pressure mechanism for 15 controlling the operation of said ramming device, a rotating shaft, and means actuated by said shaft for intermittently moving said boxes to cause them successively to be positioned in operative relation to said sand 20 delivering means and said ramming device, said fluid pressure mechanism comprising a valve adapted to be actuated by said shaft and a fluid pressure conduit operatively communicating with said ramming device and 25 said valve, a portion of said conduit being movable with said valve.

12. In a molding machine, the combination with means for slidably supporting a 30 series of mold boxes, of means for delivering sand to said boxes, a fluid pressure controlled ramming device for pressing the sand in said boxes, a conduit through which said ramming device is adapted alternately to be 35 in communication with a source of fluid pressure and with the atmosphere, a continuously rotating shaft, means actuated by said shaft for intermittently moving said boxes to cause them successively to be positioned in operative relation to said sand 40 delivering means and said ramming device, a pivoted valve having a port therein, a flexible conduit connecting said port to said first named conduit, a seat for said valve having

a port therethrough which communicates with a source of fluid pressure and also having a port which communicates with the atmosphere, and cam means carried by said shaft for oscillating said valve to position its port alternately in communication with the respective ports of said valve seat. 45 50

13. In a molding machine, the combination with means for slidably supporting a series of mold boxes, said means being provided with laterally spaced guides of unequal length for guiding said boxes, means 55 for delivering sand to said boxes, a ramming device for pressing the sand in said boxes, and means for intermittently moving said boxes to cause them successively to be positioned in operative relation to said sand 60 delivering means and said ramming device, said ramming device comprising a cylinder which is arranged above said supporting means and is rigidly connected thereto, and a piston having a rammer head which is 65 movable at right angles to the path of movement of said boxes.

14. In a molding machine, the combination with spaced members forming a horizontally extending support for a series of 70 slidable mold boxes, of vertically extending guide members of unequal length respectively secured to said spaced members and adapted to guide said boxes, a frame extending above said guide members, a chute adapted 75 to deliver sand to successive mold boxes positioned between said guides, a ramming device adapted to press the sand in said boxes, and means for moving said boxes to bring them successively into operative relation with said chute and said ramming device, said ramming device being mounted on said frame above said spaced members constituting the support for said slidable boxes. 80 85

In testimony whereof I affix my signature. THOMAS A. REYNOLDS.
